UNITED STATES PATENT OFFICE.

DUNCAN K. EASTMAN, OF CHARLESTOWN, NEW HAMPSHIRE.

CAR-COUPING.

SPECIFICATION forming part of Letters Patent No. 318,969, dated June 2, 1885.

Application filed April 4, 1885. (No model.)

To all whom it may concern:

Be it known that I, DUNCAN K. EASTMAN, a citizen of the United States of America, residing at Charlestown, in the county of Sullivan and State of New Hampshire, have invented certain new and useful Improvements in Car-Couplers, of which the following is a specification, reference being had therein to the accompanying drawings, in which—

10 Figure 1 represents a vertical sectional view of my device, and Fig. 2 is a plan view of the same.

This invention has relation to improvements in devices for coupling and uncoupling cars; 15 and it has for its object to provide means whereby a person may avoid the objectionable necessity of going between approaching cars to perform the operation of coupling and uncoupling.

20 The invention consists in the peculiar construction, combination, and adaptation of devices, as will be hereinafter more fully set forth, and specifically pointed out in the claims appended.

25 In the accompanying drawings, A indicates a frame for supporting the draw-head, the rails *a a* of which constitute the side rails of an ordinary freight or passenger car, and *b* the transverse beam of a platform, from which 30 suspends the vertical yoke B for supporting the forward end of the draw-head. The draw-head is provided on its upper side with a longitudinal slot, *c*, between the vertical walls of which are pivoted the link-securing jaw D.

35 This jaw is of a form substantially L-shaped in outline, and is provided on its upper forward longitudinal side with lateral flanges *d d*, which are designed to engage the upper side of the said draw-head. The pivoted rod 40 E, connected to the cam-lever N, within the draw-head, extends laterally therefrom, and has made fast to opposite ends thereof one half of a gimbal-joint, the opposite half being arranged on the inner ends of the operating-

45 rods F F, which are respectively supported in vertical brackets G and provided with a crank or hand lever. It will be seen that by the use of these gimbal-joints the operating-rods may be prevented from binding or twisting during 50 operation and the draw-head allowed to play without injury to any of its connections. The draw-head is also provided in its lower wall

with a vertical slot, H, which opens from the mouth a sufficient distance rearward for the reception of the pivoted jaw I. This jaw I is 55 pivoted in the said slot near its lower end. It has its forward upper side curved upwardly and inwardly or rearwardly to a transverse groove, *f*, in the upper rear end thereof, the said curved portion having a vertical longitudinal slot, *g*, for the reception of the hook *h*, formed on the forward under side of the longitudinal branch of the jaw D. This jaw I is also provided on the upper end of its vertical branch K with a shallow groove, *i*, for 65 the passage of the hook *h* and the jaw D, and the vertical branch of this jaw is designed to engage the vertical branch of the jaw D and throw the same in its slot-seat in removing the coupling-link. The draw-head is provided in 70 its inner upper wall with a downwardly and rearwardly curved guide, M, which is adapted to guide the connecting-link to the transverse groove in the vertical branch of the jaw D.

L indicates a slide-way which is provided 75 on the upper side of the draw-head in rear of the vertical slot *c*, and P is a longitudinal slide arranged therein, which is designed to engage and lock the jaw D when a connecting-link is in position. This slide is held to its seat by 80 means of a friction-spring, R, or other suitable device.

S indicates a transverse bar extending from opposite sides of the car, from the under side of which is suspended swiveled brackets T, 85 supporting the slide-operating levers *u*. These levers are slotted longitudinally at their inner engaging ends, and are connected to the rear upper side of the slide by a vertical headed stud, *m*, the opposite ends of the levers extending to the sides of the car within convenient reach of the operator.

From the foregoing description the operation and advantages of my invention will be obvious. It will be seen that when the link 95 has been inserted into the mouth of the draw-head, so as to engage the transverse groove in the vertical branch of the jaw, the hook at the forward end of the pivoted jaw D, which in its normal position rests upon the upper 100 end of the vertical branch of the said jaw, will fall into the vertical slot therein, thus securely holding the link until the said hook is raised by the operator, the jaw being simul-

taneously thrown to its seat and the link allowed to be removed. In cars used on long travels—such as passenger-cars—it is desirable to secure the link-holding devices so as to insure the engagement of the parts and prevent the same from disconnecting. To do this it is only necessary for the operator to move the slide over the jaw D by one of the hand-levers, when it will remain in such position, and the said jaw D be prevented from moving until the operation is reversed. The cam-lever N, fixed to the rod E, engages by its hook *a* the hook *b'* on the lower end of the jaw D, and serves to hold said jaw in place, and the cam portion *c'* is adapted to bear against the lower end of the jaw D, throwing the vertical portion *d'* of said jaw forward, thus raising the horizontal portion and hook *h* from engagement with the link, the slide P having been previously withdrawn rearwardly.

Having thus described my invention, what I claim is—

1. In a device for coupling cars, the combination, with the draw-head having its lower wall slotted vertically and longitudinally, of the jaw I, arranged therein, having its forward upper side curved upwardly and rearwardly to a transverse shoulder, *f*, and provided in the said curved portion with a ver-

tical longitudinal slot, *g*, adapted to receive a link-engaging hook, substantially as specified. 30

2. The combination, with the draw-head having its lower wall provided with a pivoted jaw, I, as described, of the guide arranged in the upper wall thereof, and the pivoted jaw D, having its forward longitudinal portion provided with a hook adapted to enter the slot in the said jaw, substantially as specified. 35

3. The combination of the draw-head, the link-engaging jaw, cam-lever N, the rods for operating the same, and the gimbal-joints connecting the hand-levers or rods with the pivoted rod of the link-engaging jaw, substantially as specified. 40

4. In a car-coupler, the combination, with the draw-head having the slideway and the link-engaging jaw, arranged as described, of the slide, its friction-spring, slotted hand-levers connecting the said slide, and the swiveled brackets supporting the said levers, all adapted to operate substantially as set forth. 45

In testimony whereof I affix my signature in presence of two witnesses.

DUNCAN K. EASTMAN.
